(57) **CLAIM**

The ornamental design for a shoe sole, as shown and described.

DESCRIPTION

FIG. 1 is a rear perspective view of a shoe sole, showing my new design;

FIG. 2 is a top view thereof;

FIG. 3 is a bottom view thereof;

FIG. 4 is a left side view thereof;

FIG. 5 is a rear view thereof;

FIG. 6 is a front view thereof; and,

FIG. 7 is an enlarged detail view of the area "7" in FIG. 3. The dashed broken lines in the drawings illustrate portions of the shoe sole that forms no part of the claimed design. The dash-dot-dash broken lines are used to encircle an area of enlargement and the dash-dot-dash broken lines form no part of the claimed design.
